CLAIM

The ornamental design for a soap dispenser as shown and described.

DESCRIPTION

1. Soap dispenser

1.1 : Perspective

1.2 : Front

1.3 : Back

1.4 : Left

1.5 : Right

1.6 : Top

1.7 : Bottom

The characteristic features of the design lie in the shape of the soap dispenser as shown.

The broken lines shown are for the purpose of illustrating portions of the soap dispenser that form no part of the claimed design.
